TELEVISION COMMUNICATOR

Alexander McLean Nicolson, New York, N. Y., assignor to Communication Patents, Inc., New York, N. Y., a corporation of Delaware

Application July 10, 1934, Serial No. 734,471

8 Claims. (Cl. 178—5.8)

This invention relates to communicating systems and particularly to a two-way combination system of television and telephony especially suitable for inter-office intercourse.

3 An object of the invention is to enable two parties at separated points to see and hear each other.

Another object of the invention is to provide a two-way communicator, both visual and audible, which is simple and efficient.

Still another object of the invention is to combine visual and audible reception and transmission in a desk or table device suitable for instant use.

15 Audible communicators for use over long distances, and also for inter-office service, are well known, such systems comprising audible loud speakers and a sensitive pick-up device with their associated amplifiers and transmission lines.

20 A system on these principles combining both visual and audible effects is contemplated in the present invention, the entire terminal equipment being housed within a bell-shaped horn or like housing suitable for use on a desk or 25 table. The circuit design and apparatus used to accomplish two-way television is similar and based upon a system disclosed in my co-pending application Serial No. 733,705 filed July 5, 1934. That is, the entire circuit will be practically 30 identical to the one shown in Fig. 8 of that disclosure, the present disclosure showing solely this circuit diagrammatically with the design for the terminal equipment.

The advantages and specific aspects of the 35 invention, both as to its method of operation and its fundamental principles, will best be understood from the following description when read in conjunction with the accompanying drawing in which:

40 Fig. 1 is a cross sectional view of a terminal device with the transmitting and receiving circuits shown diagrammatically, and

Fig. 2 is a front elevational view of the terminal device shown in Fig. 1.

45 In Fig. 1 a bell-shaped or open-faced housing 5 with a narrow portion 6, base 7, and bell portion 8, has included therein a light channel translator 9, the terminals of which form a surface 12 and two rings at 13. The transmitting channels which are substantially one-half of the total number and uniformly intermingled with the receiver channels at the surface 12 are capped with lenses 14 for projecting light on the object being scanned. This translator is 50 described in detail and is being claimed in my

copending application mentioned above. In brief, it consists of a plurality of light paths of unit area size formed by internally reflecting tubes of various shapes or channels made in a casting. This translator thus reduces line or 5 one-dimensional motion to a surface or two-dimensional motion so that a line of light generates a luminous field. Although there is light in only one transmitting or receiving channel at any instant the change from one channel to 10 another is sufficiently rapid to generate this light field.

An arc system 10 comprises two sets of electrodes 16 and 19 surrounded by a magnetic field 15, energy being supplied thereto through a 18 plurality of conductors 17 which terminate in the outwardly extending cable 18. This system is also fully described in the above-mentioned application. It consists of independent electrodes to create two independent arcs but with 20 a common magnetic field. The arcs provide the moving light beams which may be of different wave lengths to reduce glare and increase the efficiency of the system, while the cell 20 may be shielded by a filter to eliminate substantially 25 all light except the scanning rays.

An elongated photo-sensitive device 20, such as a photo-cell attached to the translator 9 and positioned in a portion of the space between the casing 5 and the translator 9, translates the 30 light and shade densities of an object scanned into corresponding electrical currents which are transmitted over conductors 22 to an amplifier 23 and a television transmitter 24. The output of the transmitter may be broadcast over 35 an antenna 25 or impressed on wire lines connected at 26. Incoming television signals are received on antenna 20 or at wire terminals 31 and detected by receiver 32, amplified in amplifier 33 and conducted to cable 18 over conductors 34, these conductors leading to one set of 40 arc electrodes of system. It is to be understood that the transmitter and receiver circuits are unnecessary for interoffice communication, the amplifiers 23 and 33 being sufficient for this 45 type of transmission.

For the audible portion of the system, a microphone 36 attached to translator 9 is placed in the bell portion 8 of the housing 5 similar to photo-electric cell 20, the output of which is fed 50 over conductors 37 to an amplifier 38 and sound transmitter 39, where it may be broadcast over antenna 40 or wires connected at terminals 41. The incoming sound portion of the system includes an antenna 43, wire terminals 44, sound 55

receiver 45, amplifier 46 and a loud speaking unit 47 placed in the narrow portion 6 of the housing 5. It is to be understood that the picture and sound transmitters may be combined as well as the picture and sound receivers in any well known manner. Also, the amplifiers may be enclosed within the housing which is particularly desirable for interoffice service.

10 As shown in the drawing, the housing is in two main sections lap-jointed so that the upper portion 5 may be separated for the installation of the arc equipment, the arc system being mounted on brackets 49 and 50. The bottom 15 may also be removed for access to the internal apparatus. There is space surrounding translator 9 which provides a horn for the loud speaking unit 47. It is to be noted that the device is telescopic at the narrow portion 6 to provide for 20 an elevational adjustment as well as a rotational adjustment, a set screw 21 holding the two sections in position.

The system operates in the same manner as that disclosed in co-pending application Serial 25 No. 733,705, filed July 5, 1934, mentioned above, but will be briefly described at this point. The person using this device places his face in front of and partly in the bell in a position which is controlled by the size of the bell portion 3. That 30 is, there is an optimum distance between the screen 12 and the person's face and the open portion of the device permits this optimum distance to be obtained readily as a natural act. Exterior light is thus substantially shut out producing 35 a brighter image with less light and increasing the efficiency of the transmission scanning system. The sound portion is also inclosed thus permitting the operation of the communicator without disturbing others.

40 The transmission scanning light is obtained from the rotating arc of constant intensity, this light being projected through the light channels and from the lenses 14. The reflected light from the object characterized by the light and 45 shade densities of the person's face is picked up by photo-electric cell 20 and transmitted through conductors 22 to the transmitter 24 for transmission. The incoming signals are impressed on the other electro-dynamic arc modulating it 50 in accordance with the light and shade densities of the person at the other station. This modulated light is transmitted through the receiving channels and is diffused from the surface terminals which are intermingled among the lenses 55 14. Sound such as voice will be picked up by detector 36 and transmitted in the usual manner, while the incoming sound signals will be projected from the unit 47 to the observer. There is thus provided a simple two-way 60 communicator, both visual and audible, which utilizes the same screen for picture reception and transmission scanning and utilizes the same casing for sound and picture.

It is to be understood, of course, that other 65 designs are contemplated, the one just described being for the purpose of illustration and the invention is not to be limited by the horn-type disclosed. It is also to be understood that the narrow portion 6 may be made flexible as well 70 as telescopic so as to be extended or positioned as desired, the casing 5 being decorated to harmonize or conform with the office or room decorations in which it is intended to be used.

What is claimed is:

75 1. In a television and telephone communicator,

a housing having a base and bell portion, a sound reproducer located in said base, a television translator located in said bell portion for projecting light of constant intensities in unit areas from the same surface and diffusing modulated light in unit areas, a sound pick-up device in said bell portion so positioned with respect to said translator that a person's features may be scanned while speaking therein. 5

2. In a television and telephone system, a 10 horn-shaped housing enclosing in its throat portion a sound reproducer and in its bell portion a sound pick-up device, and a television scanner and receiver located in said bell portion sufficient space being provided between said housing and said television scanner and receiver for 15 passing sound from its throat portion to its bell portion, said bell portion positioning the face of an observer at the optimum position with respect to said television scanner and receiver. 20

3. A telephone and television communicator for interoffice communication comprising a horn shaped device suitable for table and desk use, said device having a narrow portion enclosing a sound reproducer unit and an adjustable bell 25 portion enclosing a sound pick-up device, a composite television screen located in the bell portion of said device, said screen including a plurality of light transmitting channels each of which is of unit area size, substantially one-half 30 of said channels being adapted to project a beam of light of constant intensity and the remainder of said channels being adapted to project diffused light varying in intensity in accordance with an object scanned at a distant point, said 35 channels being curved so that the projecting terminals thereof are in a substantially vertical plane and the receiving terminals are in a substantially horizontal plane, a photoelectric cell located in the bell portion of said device for 40 detecting projected light from an object scanned, and means for producing a plurality of moving light beams for supplying light to the receiving terminals of said channels.

4. A communicator in accordance with claim 45 3 in which said last mentioned means comprises a plurality of moving electrical discharges along stationary electrode rails positioned in a stationary magnetic field.

5. In a system of sound and picture transmission, stationary means for projecting a light beam of constant intensity over an object to be scanned, stationary means for diffusing light over said object, stationary means for producing moving light beams, for supplying light to said 55 projecting and diffusing means, one of said beams emitting light of constant intensity and the other of said light beams emitting light of varying intensity in accordance with the light and shade densities of an object, means for detecting sound waves, means for detecting light waves, said light and sound detecting means being positioned adjacent said first mentioned means, means for reproducing sound waves, and means for enclosing all of said above mentioned 65 means in a compact unitary arrangement, said last mentioned means serving as a horn for directing sound waves to a listener, as means for localizing the sound to said listener only, as means for shielding said light projecting means, 70 and as means for positioning the face of a listener in an optimum scanning position.

6. In a communicating system, stationary means for projecting a light beam over an object to be scanned, stationary means inter- 75

mingled with said first means for diffusing over the same area light modulated in accordance with the light and shade densities of an object at a distant point, stationary means for producing a moving light beam of constant intensity, stationary means for producing a moving light beam varying in intensity in accordance with the light and shade densities of an object at a distant point, a sound reproducer located adjacent said last mentioned means, and a housing for all of said above mentioned means, said housing providing a horn for said sound reproducer, a sound localizer for a listener, a light shield and means for positioning an object to be scanned in an optimum position.

7. In a television and telephone communication system, an adjustable horn shaped housing suitable for desk use having an open end in a substantially vertical plane and a closed end in a substantially horizontal plane, a television scanning and receiving screen located within the

open end of said housing and in a substantially vertical plane, a light detector and a sound detector, both of said detectors being located adjacent said screen, a telephone receiver located at the closed end of said housing and means having solely stationary parts for obtaining a moving beam of light also located at the closed end of said housing, said elements above mentioned being so positioned within said housing as to provide a space between said housing and said elements for confining and directing sound to an observer.

8. A television and telephone communication system in accordance with claim 7, in which the open portion of said housing may be rotated, raised and lowered and is shaped to position the face of an observer at the optimum point with respect to said television scanning and receiving screen, said screen having an area comparable to the size of the face.
